UNITED STATES PATENT OFFICE.

ALPHONSO COMSTOCK PRATT, OF DEEP RIVER, CONNECTICUT.

BEAD-CABLE FOR AUTOMOBILE-TIRES.

1,386,072.

Specification of Letters Patent. Patented Aug. 2, 1921.

Application filed January 20, 1921. Serial No. 438,577.

To all whom it may concern:

Be it known that I, ALPHONSO COMSTOCK PRATT, a citizen of the United States, residing at Deep River, in the county of Middlesex, State of Connecticut, have invented certain new and useful Improvements in Bead-Cables for Automobile-Tires; and I do hereby declare the following to be a full, clear, and exact description of the invention, such as will enable others skilled in the art to which it appertains to make and use the same.

This invention relates to bead cables or grommets adapted particularly for use in the beads of the casings for automobile tires, especially those of the straight side type.

In accordance with this invention, the bead cable consists of a core and a casing surrounding this core and wholly disconnected from it, the casing being formed of a plurality of convolutions of spirally formed wire with the spirals of the several convolutions lying side by side around the core. Such a bead cable can be made at relatively low cost, particularly when the casing is made of "preformed" wire, that is, wire which is bent to its spiral configuration before it is applied to the core. Also, with a bead cable constructed in this manner, the casing being wholly disconnected from the core, may turn more or less about the core during the process of manufacturing a casing without any change in the relation of the several convolutions constituting the casing, such as would cause bursting strains on the bead cable to be assumed unequally by the several convolutions. This is of special advantage in connection with certain processes of manufacturing automobile tires.

The core for a bead cable constructed in accordance with the invention preferably consists of a single piece of wire of the requisite diameter which is bent to a circle and has its ends joined together in any suitable manner as by welding, so as to form a hoop which is of uniform cross section at all points.

The casing of convolutions of spirals is applied to this core without permanently connecting it to the core. If desired, the end of the wire from which the casing is formed may be temporarily attached to the core to facilitate the process of spiraling the wire, but if so, it is subsequently disconnected from the core. Preferably the wire for the casing is not attached to the core

at any time. Instead, the wire is preformed by giving it its spiral configuration before it is applied to the core. This may be done by the employment of a winding machine of the type illustrated and described in Patent No. 1,294,160 granted to me on February 11, 1919. In such a machine, the wire for the casing is fed through a spirally formed die so that the wiring issuing from the die is in the form of a succession of spirals and the wire thus formed is laid upon the core to form a plurality of convolutions of spirals inclosing the core with the spirals of the several convolutions lying side by side. To do this, the previously formed hoop constituting the core is placed in the winding machine and a separate wire is fed through the die of the machine to spiral the wire and then lay it upon the core. The grip of the spirals of the spirally formed casing wire is quite sufficient to carry the core around in the guide or holder for the bead cable being formed after the first spiral or two have been applied to the wire. Preferably the casing of convolutions of spirals consists of six convolutions. When the desired number of convolutions of spirals have been applied to the core, the wire from which the casing is formed is cut at such a point that when the end of the wire where the cut is made is applied to the cable, it will abut against the other end of the casing wire. These two ends may be joined together in any suitable manner as by welding them, but such connection of the ends of the casing wire is unnecessary. Even if the ends of the casing wire are not joined, a bursting strain imposed upon the cable will not cause these ends to be raised from the cable as the strain on the convolutions of spirals will cause them to grip the core the more tightly.

The preferred embodiment of the invention is illustrated in the accompanying drawings in which Figure 1 is a view of the core; Fig. 2 is a view of the completed cable; Fig. 3 is a view on enlarged scale of a portion of the cable shown in Fig. 2, and Fig. 4 is a cross-section on line 4-4 of Fig. 3.

Referring to these drawings, Fig. 1 shows the core formed from a single piece of wire bent to circular form and having its ends welded together as shown at 2.

The casing 3 of convolutions of spirals is applied to this core 1, six convolutions of spirals being employed preferably and these being arranged in the manner indicated in

- Figs. 3 and 4. The wire for the convolutions of spirals may be wound spirally under tension upon the core 1 but preferably the wire is preformed so as to give it its spiral configuration before it is applied to the core. The ends of the wire from which the casing is formed abut as is shown at 4 and these ends may be welded together or may remain disconnected as desired.
- 10 It will be noted that the cable constructed as above described consists of two pieces of wire, one forming the core and the other forming a casing inclosing the core but wholly disconnected from it. Because of 15 this characteristic of the construction, the casing as a whole is free to be moved angularly more or less about the core and since each convolution of the casing is a succession of similar spirals throughout its length, 20 any such angular movement of the casing about the core will not effect any change in the relative lengths of the several convolutions. Therefore, a bursting strain imposed upon the cable will be resisted equally 25 by all of the convolutions of spirals irrespective of whether or not there has been any angular movement of the casing about the core. This characteristic of the cable is of special value in tire casings which are made 30 initially in the form of a flat band and then expanded or distended throughout the central portion of the band to cause the band to assume the configuration of a tire casing. In such shaping of a flat band to the form 35 of a casing, the edge portions of the band which form the beads of the cable, turn through an angle approximating 90° and during this angular movement of the beads, the casings of the cables may turn more or 40 less upon their cores, and the casings in their new relation will be capable of withstanding the strains to which the beads of the casing are subjected without any distribution of the strain upon the several convolutions of
- the cable. As stated above, the ends 4 of 45 the wire for the casing need not be joined together. The imposition of a bursting strain upon the cable will not cause these ends to rise from their positions. Nevertheless, it may be desirable to secure the ends 50 of the casing wire in some manner so as to prevent them from being raised from their positions accidentally. These ends may be welded together or they may be secured in position by solder or a band of sheet metal 55 may be laid around the cable overlying the ends 4 of the casing wire and the ends of this sheet metal band may be secured together in any suitable manner.
- I claim:
1. A bead cable comprising the combination of a core and a casing on the core consisting of a plurality of convolutions of spirals with the spirals of the several convolutions lying side by side, the core and the 60 casing being wholly disconnected one from the other so that the casing as a whole may move angularly upon the core.
2. A bead cable comprising the combination of a core and a casing on the core consisting of a plurality of convolutions of spirals with the spirals of the several convolutions lying side by side, the casing being wholly disconnected from the core and having the ends of the piece of wire from which 65 it is formed abutting.
3. A bead cable formed from two pieces of wire, one constituting a core and having its ends welded together to form a hoop and the other constituting a casing consisting 70 of a plurality of convolutions of spirals with the spirals of the several convolutions lying side by side about the core, the casing being disconnected from the core and having the ends of the piece of wire from which it is 75 formed abutting.

In testimony whereof I affix my signature.

ALPHONSO COMSTOCK PRATT.
